THREAD CONTROL MECHANISM FOR WEFT
REPLENISHING LOOMSRichard G. Turner, Worcester, Mass., assignor to
Crompton & Knowles Loom Works, Worcester,
Mass., a corporation of Massachusetts

Application August 26, 1944, Serial No. 551,287

3 Claims. (Cl. 139—257)

1

This is a continuation in part of my copending application Serial No. 526,033, filed March 11, 1944, now Patent No. 2,390,014.

This invention relates to improvements in thread control mechanisms for weft replenishing looms and it is the general object of the invention to provide means by which the thread of the transferred bobbin may be effectively removed from the loom.

Weft replenishing mechanisms more particularly of the multicolor type employ a magazine provided with a series of reserve bobbins from which weft ends extend. These weft ends are generally led to some form of thread holder serving as an anchorage to assist in threading the shuttle during the pick immediately following a transferring operation. It has been proposed heretofore to utilize pneumatic thread holders which operate by means of a draft of air not only to hold the weft ends taut and assist the shuttle threading operation but also to remove the thread of the transferred bobbin after cutting at the selvage. The thread of the transferred bobbin extending from the thread holder and awaiting cutting at the selvage should preferably be held in such position that it will not interfere with a second bobbin should another transfer be called prior to cutting of the thread. It is accordingly an important object of my present invention to provide a hook or the like which will hold the thread of the transferred bobbin in an advanced position out of the path of the bobbin moving from the magazine into the shuttle. In this connection I provide means for placing the thread of the transferred bobbin over its hook or the like before a second transfer can occur.

It is another object of the invention to provide the pneumatic thread holder with an intake mouth formed on the end of a tube so disposed that the thread engaging notch of the hook lies substantially on the tube axis. By this arrangement the hook serves as a guide to direct the thread when the latter is cut along a path leading into the mouth of the thread holder without engaging the periphery of the latter.

It is another object of the invention to provide a hook mounted preferably on the stationary part of the loom and utilize a thread placer mounted on the lay in position to move the thread of the incoming bobbin over and onto the stationary hook. The latter is preferably higher than the placer so that during succeeding forward movements of the lay the thread on the hook will not be disturbed by the placer.

In looms of the general type to which my in-

2

vention more particularly relates it is customary to employ a pneumatic thread remover in addition to the thread holder. The remover is located between the magazine and the selvage and acts upon the thread of the outgoing bobbin in such manner as to remove it from the path of the shuttle. Heretofore the thread of the incoming bobbin has been so located that its inner end could be attracted by the thread remover, in which event both ends of the threads are drawn into pneumatic devices neither one of which is strong enough to overpower the other. As a result the thread hangs suspended between the thread holder and the thread remover where it can be broken and be drawn into the warp shed.

It is another important object of my present invention to place the aforesaid hook in such relationship relatively to the thread remover that the latter will not be able to attract the inner end of the thread of the incoming bobbin. This result I accomplish by locating the hook far enough forwardly of the lay to cause the thread of the incoming bobbin to form a relatively large angle with the thread of the outgoing bobbin which extends to the remover. Under these conditions there is little or no likelihood that the incoming thread can approach the mouth of the thread remover.

After the first beat-up following a transfer operation there are ordinarily two threads leading from the selvage, the front thread having been laid by the outgoing bobbin extending to the thread remover and the rear thread having been laid by the incoming bobbin extending to the aforesaid hook. The incoming thread is therefore behind the thread of the outgoing bobbin and under normal conditions would be cut either after or simultaneously with cutting of the thread of the outgoing bobbin. When this order of cutting occurs it is found that entanglement of the two threads sometimes results causing the incoming thread to be drawn into the remover. It is another object of my invention to cross the aforesaid two threads close to the selvage and lead the last of the threads to be laid, that is, the incoming thread, to a position in front of the other thread which was laid a pick earlier. The thread thus advanced is moved forwardly far enough to permit cutting of it before the other thread is cut, thereby avoiding the aforesaid entanglement. Immediately upon cutting the pneumatic thread holder will draw the front thread away from both the selvage and the thread remover and the thread of the outgoing bobbin may then be cut on a later pick without

danger that it will draw the thread of the incoming bobbin into the thread remover.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of part of a weft replenishing loom having my invention applied thereto.

Fig. 2 is a plan view looking in the direction of arrow 2, Fig. 1, and showing part of the structure shown in Fig. 1 on an enlarged scale.

Fig. 3 is a diagrammatic view showing the 15 thread hook and thread placer in side elevation as they appear in Fig. 1, but on an enlarged scale, and indicating the manner in which the placer locates the thread over the hook as the lay advances on the beat-up immediately following transfer,

Fig. 4 is a fragmentary view similar to a part of Fig. 3 but showing how the placer passes under the thread on the hook during later beat-ups of the lay, and

Fig. 5 is a diagrammatic plan view showing the relation of the two threads, the selvage, the hook and placer, and the pneumatic attachments connected to their respective threads.

Referring particularly to Figs. 1 and 2, I have shown a loom frame 10 having a lay 11 driven by connectors 12 attached to the usual top or crank shaft 13. The lay is provided with a shuttle box 14 which receives a shuttle S containing a bobbin B. A magazine M having front and back bobbin guideways 15 and 16, respectively, has extending therefrom a series of weft ends W leading from the reserve bobbins R in the guideways 15 and 16. The magazine is provided with a transerrer arm 17 pivoted as at 18 and having a latch 19 for cooperation with a bunter 20 on the lay. A weft detector D of any approved form may be used for determining the condition of weft on the bobbin B. A setting head 21 is lifted by mechanism not shown but under control of the weft detector, and when the head rises it lifts the latch 19 into the path of the bunter 20, thereby causing the transerrer arm to move a bobbin from the magazine into the shuttle S as the lay approaches front center.

An air pump 25 is secured in any approved manner to the loom frame and has a piston 26 connected to a lever 27 pivoted as at 28 to some fixed support. An operating rod 29 extends forwardly from the lever and is connected as at 30 to the lay. A pipe or tube 32 leads from the pump to the upper part of a thread accumulator A, and creates subatmospheric pressures in the latter as the lay recedes. Extending from the accumulator is a second tube 33 which leads to a pneumatic thread remover 34 located between the magazine and the fabric F. The thread remover is normally raised but is depressed at the time of transfer. A tube or cylinder 35 extends from the accumulator A toward the magazine and has an intake mouth 36 through which air drawn into tube 35 tends to draw the weft ends W. The accumulator A and the tube 35 may be supported on a bracket 37 fastened to the loom frame. Mechanism designated generally at 38 may be employed for rocking the magazine M so that the lowest bobbin of either of the stacks 15 or 16 may be located under the transerrer arm 17. The mouth 36 communicates with the interior of the

accumulator through an air passage 39 in well known manner.

A thread cutter designated at 40 is provided with a blade 41 which is positioned to enter an aperture 42 in the box front 43 when the lay moves forwardly during a transfer operation, otherwise the cutter is held forwardly by a part 44 of the transfer mechanism. When the cutter blade 41 is in rear position, however, it serves to cut the thread T extending from the bobbin B through the shuttle eye E and along the front wall 43 to the selvage 45 of the fabric. A temple 46 is provided with a temple cutter designated at 47.

In the operation of the mechanism thus far described the lay reciprocates back and forth in the usual manner and the shuttle is picked by mechanism designated at 48 when the lay is approximately half way between its front and back positions and moving rearwardly. The shuttle enters the box 14 while the lay is moving forwardly and the detector D performs its detecting operation when the lay is in the front center position indicated in Fig. 1. During the backward stroke of the lay the pump 25 creates subatmospheric pressures within the accumulator A and thereby draws air into the intake mouth 36 and through tube 35, and also draws air into the thread remover 34. When the transerrer arm is depressed the cutter blade 41 will move rearwardly to cut the thread T adjacent to the shuttle eye E and at the same time the lowest bobbin in one or the other of the stacks 15 or 16 will be moved from the magazine into the shuttle S, thereby effecting the downward movement of the corresponding weft end W. As shown in Fig. 1, bobbin B' in stack or guideway 15 is in position for transfer. These operations occur while the lay is on front center and as the lay moves rearwardly the thread T will approach the thread remover 34 which has been temporarily lowered to thread receiving position, after which the shuttle is picked, thereby freeing that part of thread T between the shuttle and the box front 43. The thread remover 34 thereupon draws the right end of the thread T into itself and the left end of the thread T extends from the remover 34 to the selvage 45. On the next beat-up of the lay the thread W' of the transferred bobbin is beaten to the fell of the cloth 50 by means of the reed 51 on the lay. The thread of the transferred bobbin is therefore one pick behind the thread of the outgoing bobbin and both of these threads extend from the selvage to the right. The temple cutter 47 is of the usual type and has a thread cutting operation at every forward beat of the lay, but its range of operations is several picks in advance of the fell 50.

The matter thus far described is of common construction and of itself forms no part of my present invention. For further understanding of the structure and operations involved reference may be had to the following patents: 2,199,353; 2,199,296; 2,199,354 and 2,326,905.

In carrying my present invention into effect I provide means for holding the thread W' in a position forward of the lay where it will not interfere with a transfer and where it can be cut prior to the cutting of thread T. Accordingly, I mount a hook 60 on a stationary stand 61 for the magazine and provide the hook with a slot 62 receiving a screw 63 threaded into part 61, thereby permitting the hook to be adjusted as to its back and forth position. The hook is provided with a notch 64 which faces forwardly, and there is an upward-

* ly and forwardly extending guide surface or edge 65 on the hooks leading to the notch 64. As shown in Fig. 2 the hook is considerably in advance of the shuttle box and lay when the latter is on front center position.

Mounted on the lay is a thread placer 70 having a front upwardly and rearwardly inclined thread engaging edge or surface 71 the upper part of which leads to a hook or notch 72. The placer 70 may be secured as at 73 to the front part of the lay, see Fig. 2, and is ordinarily at such an elevation that it will pass below the notch 64 of the stationary hook.

During the beating-up of the lay immediately after picking of the replenished shuttle the thread W' is engaged by edge 71 and moved into notch 72. As the lay advances the thread W' is moved forwardly up the inclined surface 65 and into the notch 64. This part of the operation is indicated in Fig. 3, where the thread placer 70 is indicated in full line position behind the thread W', while the dotted line position shows the thread after it has been moved into notch 64. The thread placer then moves forwardly from the dotted position of Fig. 3 to the dotted line position of Fig. 4, reaching this position when the lay is on front center. As the lay recedes the placer moves along a path under the thread W' as suggested in full lines in Fig. 4 and on all subsequent beat-ups of the lay the placer will pass below the thread W'.

As indicated in Figs. 2 and 5 the tube 35 and the hook 60 are so related that the notch 64 lies substantially on the axis of the tube. The right hand part of the thread W' shown in Fig. 5 therefore leads from the hook or notch 64 into the air passage in tube 35 without touching the periphery of the intake mouth 36. Even though back and forth adjustment of the hook 60 is made by means of the slot 62 and the screw 63, the adjustment will not, however, disturb the essential relationship between the tube 35 and the thread W' as already described, since in any of the adjusted positions of hook 60 the thread W' will enter tube 35 without touching the circumference of mouth 36.

Another important relationship of the threads effected by my invention is shown in Fig. 5. The thread remover 34 normally causes the thread T to lie in a vertical plane substantially parallel to the lay. The hook 60, however, is so placed that the left hand part of the thread W' leads forwardly and to the right from the selvage in an oblique direction and away from the thread T. As already stated thread W' is connected to the selvage at a point one pick behind the point of attachment of the thread T of the selvage, hence the hook 60 causes a crossing of these threads near the selvage and then a separation of them, as is clearly indicated in Fig. 5. Because of this separation the temple cutter 47 first cuts the thread W', permitting it to be drawn away from the selvage before the thread T is cut by the temple cutter. There is therefore no danger that the thread W' will become entangled with the thread T when the latter is cut.

The notch 64 of the hook 60 is located not only in a position in front of a line drawn from the thread holder to the fell of the cloth, but is also located above that line so that the bend in the thread W' is partly upward and partly forward. When being tensioned by the thread holder therefore the thread W' exerts a light downward force as well as a light rearward force on the hook 60, and is thus held in the notch 64.

From the foregoing it will be seen that I have

provided simple means for controlling the weft end W' of the incoming bobbin by means which places it on a hook which holds the thread in a position forwardly of the lay when the latter is on front center so that the thread will not interfere with a downwardly moving bobbin should a second transfer occur before the thread is cut by the temple cutter 47. It will also be seen that the lay carries a thread placer which normally traverses a path below the thread W' but is operative to move the latter up the inclined surface 65 of the hook 60. Also, the notch 64 is located more or less on the axis of the tube 35 and the air passage through it so that the part of the thread extending from the hook toward the thread holder will enter the latter without engaging the periphery of the intake mouth 36. The hook 60 is located between the thread holder and the cutter 47, and is so located that it causes the thread W' to be cut before thread T is cut, despite the fact that the latter thread is one pick ahead of the thread W'. This cutting of the thread of the incoming bobbin prior to the cutting of thread of the outgoing bobbin avoids entanglement of the two threads and prevents thread W' from being drawn into the thread remover 34.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a lay and a reserve bobbin transferred during a replenishing operation from a magazine into a shuttle which is subsequently picked away from the magazine, a pneumatic thread holder tending to draw said thread through an intake mouth thereof and into a thread passage therein, a stationary hook having a thread notch located on a straight line extending into said passage without touching the perimeter of said mouth, said hook having a rear edge extending upwardly and forwardly behind said notch, means on said lay moving in a path below said notch and operative subsequent to said picking of the shuttle to move said thread up said edge and into said notch, and cutter mechanism operative thereafter to cut the thread at a point on that side of the hook opposite to said thread holder, whereupon said thread is drawn into said passage along said line.

2. In a weft replenishing loom having a reserve bobbin transferred during a replenishing operation into a shuttle which is subsequently picked to lay a weft thread which becomes attached to the cloth selvage, a pneumatic thread holder tending to draw the thread into a thread passage therein, a hook having a thread notch located substantially on the axis of said passage and in front of and at a level above a straight line extending from the thread passage to the point of attachment of the thread to the selvage, means operating subsequent to picking of the shuttle to move the thread into said notch, and a cutter parting the thread between the hook and selvage, whereupon the thread is drawn into said passage along a line extending from said notch into said passage.

3. In a weft replenishing loom having a reserve bobbin transferred during a replenishing operation into a shuttle which is subsequently picked to lay a weft thread which becomes attached to the cloth selvage, a pneumatic thread holder tending to draw the thread into a thread passage therein,

a hook having a thread notch located substantially on the axis of said passage and at a level above a straight line extending from the thread passage to the point of attachment of the thread to the selvage, means operating subsequent to picking of the shuttle to move the thread into said notch, and a cutter parting the thread between the hook and selvage, whereupon the thread is drawn into said passage along a line extending from said notch into said passage.
